ATTORNEY'S

UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

HOPPER DUMP-CAR.

963,862.

Specification of Letters Patent. Patented July 12, 1910.

Application filed March 11, 1910. Serial No. 548,516.

To all whom it may concern:

Be it known that I, ARGYLE CAMPBELL, a citizen of the United States, residing in Chicago, in the county of Cook and State of Illinois, have invented a new and useful Improvement in Hopper Dump-Cars, of which the following is a specification.

My invention relates to improvements in hopper dump cars.

10 The object of my invention is to provide a hopper car with inside dump, which will be of a strong, simple, efficient and durable construction, composed of few parts and capable of being cheaply manufactured.

15 The invention consists in the means employed to accomplish this object or result as herein shown and described, and particularly specified in the claims.

20 In the accompanying drawing forming a part of this specification, Figure 1 is a plan view of my improved dump car, one-half the length of the car body being omitted to enable the construction to be shown on a larger scale and more distinctly. Fig. 2 is

25 a side elevation. Fig. 3 is an end elevation, partly in cross section, on lines 3—3 and 3^a—3^a of Fig. 2. Fig. 4 is an enlarged detail section on line 4—4 of Fig. 2 and Fig. 5 is a detail side elevation looking in the 30 direction of the arrow marked 5 in Fig. 4. Fig. 6 is a detail plan view of the winding drum and connecting links. Fig. 7 is a detail elevation of same and Fig. 8 is a detail front or edge view of same.

35 In the drawing, 1 represents the body of my dump car, 2 the upright side sheets of the car body, secured to the upright posts or frame members 3, 4 the side hopper sheets, 5, 6 the inclined end floor sheets, 7 central longitudinal inside hopper sheets and 8 the center sills of the car body.

40 The hopper bottom of the car body is provided with a plurality of door openings 9, the same being separated at their ends by the transverse hopper sheets 10 and closed by the doors 11, which are connected by hinges 12 at their upper inner edges 13 to the hinge butts or brackets 14 which are secured to the center sills 8.

45 50 55 15 are the door operating shafts, extending longitudinally of the car, one on each side and near the outer edge, the same being journaled in suitable bearings on the brackets 16, which are secured to and below the side hopper sheets 4. Each of the operating

shafts is provided with a plurality of polygonal, preferably four sided, winding drums 17, having pivot ears or lugs 18, which are connected by a plurality of links 19, 20 and 21 with the doors 11. Each of the winding drums is provided on one side or face with a locking shoulder 22, and one of the connecting links, preferably the middle one, is also provided with a corresponding and coöperating shouldered locking face 23. The link 21, which is pivoted at one end to the door, is preferably furnished with a right angle bend 24, so that the short link 20, which is provided with a locking shoulder or face 23, may engage the drum when the door is closed centrally and directly opposite the axis of the operating shaft. The operating shaft 15 is provided with a ratchet 25, the teeth of which are engaged by a locking pawl 26. The operating shaft is also provided with fulcrum pins 27, for engagement with the spike or lever by which the shaft is turned or operated.

28 The side sheet 2 is provided with flanges 29 fitting under the end floor sheet 5 and 30 outside hopper sheet 4. And the end floor sheet 5 is in turn furnished with inner flanges 29, fitting inside the side sheet 2 and outside hopper sheet 4. And the outside hopper sheet 4 is furnished with flanges 30 on the 35 outside of the end floor sheet 5 and inside the side sheet 2, thus making an exceedingly strong, and at the same time very simple and efficient construction and connection of the several side sheets, end floor sheets and outside hopper sheets of the dump car body.

I claim:

1. In an inside dump hopper car, the combination with the center sills, upright side sheets, inclined end floor sheets, longitudinal inside hopper sheets and longitudinal outside hopper sheets, of doors, hinge brackets secured to the center sills under the inside hopper sheets, and an operating shaft, winding drums thereon, supporting brackets for said shaft secured under said outside hopper sheet, and connecting links between said drums and doors, substantially as specified.

2. In an inside dump hopper car, the combination with the center sills, upright side sheets, inclined end floor sheets, longitudinal inside hopper sheets and longitudinal outside hopper sheets, of doors, hinge brackets secured to the center sills under the inside hopper sheets, and an operating shaft, wind-

- 2
- ing drums thereon, supporting brackets for said shaft secured under said outside hopper sheet, and connecting links between said drums and doors, said drums having shouldered locking faces and a connecting link for each drum having a coöperating shouldered locking face, substantially as specified.
3. In an inside dump hopper car, the combination with the center sills, upright side sheets, inclined end floor sheets, longitudinal inside hopper sheets and longitudinal outside hopper sheets, of doors, hinge brackets secured to the center sills under the inside hopper sheets, and an operating shaft, winding drums thereon, supporting brackets for said shaft secured under said outside hopper sheet, and connecting links between said drums and doors, said upright side sheets being flanged under said end floor sheets, substantially as specified.
4. In an inside dump hopper car, the combination with the center sills, upright side sheets, inclined end floor sheets, longitudinal inside hopper sheets and longitudinal outside hopper sheets, of doors, hinge brackets secured to the center sills under the inside hopper sheets, and an operating shaft, winding drums thereon, supporting brackets for said shaft secured under said outside hopper sheet, and connecting links between said drums and doors, said upright side sheets being flanged under said end floor sheets, and under said outside hopper sheets, substantially as specified.
5. In an inside dump hopper car, the combination with the center sills, upright side sheets, inclined end floor sheets, longitudinal inside hopper sheets and longitudinal outside hopper sheets, of doors, hinge brackets secured to the center sills under the inside hopper sheets, and an operating shaft, winding drums thereon, supporting brackets for said shaft secured under said outside hopper sheet, and connecting links between said drums and doors, said upright side sheets being flanged under said end floor sheets, and said end floor sheets being in turn flanged inside of said side sheets, substantially as specified.
6. In an inside dump hopper car, the combination with the center sills, upright side sheets, inclined end floor sheets, longitudinal inside hopper sheets and longitudinal outside hopper sheets, of doors, hinge brackets secured to the center sills under the inside hopper sheets, and an operating shaft, winding drums thereon, supporting brackets for said shaft secured under said outside hopper sheet, and connecting links between said drums and doors, said upright side sheets being flanged under said end floor sheets, and said end floor sheets being in turn flanged inside of said side sheets, substantially as specified.
7. In an inside dump hopper car, the com-

- bination with the center sills, upright side sheets, inclined end floor sheets, longitudinal inside hopper sheets, and longitudinal outside hopper sheets, of doors, hinge brackets secured to the center sills under the inside hopper sheets, and connecting links between said drums and doors, said upright side sheets being flanged under said end floor sheets and under said outside hopper sheets, and said end floor sheets being in turn flanged inside of said side sheets and outside hopper sheets, substantially as specified.
8. In an inside dump hopper car, the combination with the center sills, upright side sheets, inclined end floor sheets, longitudinal inside hopper sheets, and longitudinal outside hopper sheets, of doors, hinge brackets secured to the center sills under the inside hopper sheets, and an operating shaft, winding drums thereon, supporting brackets for said shaft secured under said outside hopper sheet, and connecting links between said drums and doors, said upright side sheets being flanged under said end floor sheets and under said outside hopper sheets, and said end floor sheets being in turn flanged inside of said side sheets, and outside hopper sheets, substantially as specified.
9. In a dump car, the combination with a dump car body, of a hinged door, an operating shaft, a polygonal drum on said shaft having a shouldered locking face and a pivot lug, of a connecting link pivoted to said lug, a short intermediate connecting link, a shouldered locking face on said intermediate link engaging the shouldered locking face of said drum, and a long connecting link, extending from said intermediate link to the door, substantially as specified.
10. In a dump car, the combination with a dump car body, of a hinged door, an operating shaft, a polygonal drum on said shaft having a shouldered locking face and a pivot lug, of a connecting link pivoted to said lug, a short intermediate connecting link, a shouldered locking face on said intermediate link engaging the shouldered locking face of said drum, and a long connecting link, extending from said intermediate link to the door, said long link having a bent end, substantially as specified.
11. A dump car body having upright side sheets, inclined end floor sheets, outer longitudinal hopper sheets and inner longitudinal hopper sheets, said upright side sheets being flanged under said end floor sheets and said outer hopper sheets, substantially as specified.

12. A dump car body having upright side sheets, inclined end floor sheets, outer longitudinal hopper sheets and inner longitudinal hopper sheets, said upright side sheets being flanged under said end floor sheets and said outer hopper sheets, said end floor sheets being in turn flanged inside of said side sheets and outer hopper sheets, substantially as specified.
13. A dump car body having upright side sheets, inclined end floor sheets, outer longitudinal hopper sheets and inner longitudinal hopper sheets, said upright side sheets being flanged under said end floor sheets and said outer hopper sheets, said end floor sheets being in turn flanged inside of said side

sheets and outer hopper sheets, and said outer hopper sheets being in turn flanged on the outside of said end floor sheets and inside said upright side sheets, substantially as specified.

14. In a center dump car of the class specified having center sills and an outside hopper sheet, the combination of doors hinged on or near the center sills, with an operating shaft for said doors having bearings under and attached to said outside hopper sheet, substantially as specified.

ARGYLE CAMPBELL.
